arm 33 of a cocking lever 34 (Figs. 1 and 2) which is mounted on the breech block by means of a pivot pin 35. The upper extremity of the cocking lever extends above the breech ring A so that it may be manually actuated with the breech block B in closed position. Normally the cocking lever is adapted to be initially rotated during lowering of the breech block by engagement with the breech ring and it is provided with a lug 36 which rides over a pin 37 carried by the breech ring to provide for the final rotation. The inner end of pin 37 extends into a slot 37a in the breech block. A plunger 38 acts on the lower arm 33 to normally maintain the lower arm in the forward position.

During lowering of the block the cocking lever retracts the guide 12 and firing pin and holder to the position shown in Fig. 5, thereby compressing the spring 11. During this retraction the cam lug 17 moves the sear 39 (Fig. 13) laterally against the action of sear spring 40. When the lug 17 clears the sear, the latter is restored by its spring to be interposed in the path of the lug 17 and in this manner the sear holds the firing mechanism in cocked position.

A trigger 41 (Figs. 9 and 10) rotatably mounted in the breech ring includes a tripper 42 which engages a cam 43 on the sear 39 to move the sear laterally of the block and out of engagement with the lug 17 on the guide 12. The means for actuating the trigger is illustrated as a rod 44 which is mounted on a non-recoiling gun carriage in a known manner.

The trigger 42 has a depending arm 45 with an inwardly directed finger 46 extending across the front face of the breech block. When the block is closed preparatory to firing, the actuation of the trigger to disengage the sear moves the finger 46 into a recess 47 in the front face of the block. The finger is cammed out of this recess when the block is lowered. In any other position of the block the finger is restrained by the front face of the block so that this provision positively prevents movement of the trigger to fire the gun except when the breech block is closed. A plunger 48 is provided for normally moving the trigger to the non-firing position.

When the firing mechanism is in the cocked position as seen in Fig. 5, the spring 11 is compressed and the sleeve 9 is seated against the cap 26. When the sear is disengaged through actuation of the trigger, the spring 11 acts through the collar to drive the guide and firing pin forward (Fig. 4). The fingers 21 on engaging the plug 7 arrest the forward motion of the collar but the firing pin, under the influence of inertia, continues forward to strike the primer of a cartridge C. During this movement the head 22 of the firing pin holder acting on the inturned flange 23 of the sleeve 9 moves the sleeve forwardly to further compress the spring 11. The spring, in recovering, immediately moves the sleeve rearwardly against the cap and the flange 24 by virtue of its engagement with the head 22, retracts the firing pin to a position within the plug so that it will not interfere with opening of the breech block. The further retraction of the guide by the cocking lever has been previously described.

I claim:

1. In a firing mechanism, a breech block having a bore, a hollow guide slidable within the bore and having an apertured front end, a firing pin carried by the front end and having a rear portion with a head disposed within the

guide, a collar slidable within the guide and on the firing pin and having fingers projecting forwardly through the front end of the guide to engage the breech block, a sleeve slidable within the bore and having an outwardly turned flange on its rear end and an inwardly turned flange on its front end engageable with the front face of the head on the firing pin, a spring confined between the collar and the rear flange of the sleeve, and means for confining the rear end of the sleeve.

2. In a firing mechanism, a breech block having a bore, a hollow guide slidable within the bore and having an apertured front end, a firing pin carried by the front end and having a rear portion with a head disposed within the guide, a collar slidable within the guide and on the firing pin and having fingers projecting forwardly through the front end of the guide to engage the breech block, a sleeve slidable within the bore and having means for engaging the front face of the head of the firing pin, a spring confined between the collar and the sleeve, means for confining the rear end of the sleeve, and means for retracting the hollow guide to cock the firing pin.

3. In a firing mechanism, a breech block having a bore, a hollow guide slidable within the bore and having an apertured front end, a firing pin carried by the apertured front end of the guide and extending on opposite sides of said front end, a collar slidable within the guide and having fingers projecting through the front end of the guide, a sleeve slidable within the bore and having mutually actuating engagement with the firing pin, a spring confined between the collar and the sleeve, means for confining the rear end of the sleeve, and means for retracting the hollow guide to cock the firing pin.

4. In a firing mechanism, a breech block, a firing pin member slidable in the breech block, a front spring seat collar engageable with the firing pin member, means for limiting forward movement of the collar short of the firing pin member, a rear spring seat member having mutually actuating engagement with the firing pin member, a spring confined between the rear spring seat member and the front spring seat collar, means for confining the rear end of the rear spring seat member, and means for retracting the hollow guide to cock the firing pin.

5. In a gun, a breech ring, a vertically sliding breech block in the breech ring, a firing pin in the breech block, a cocking lever pivotally mounted in the breech block above the firing pin and extending above the breech ring to be in position for manual actuation, said cocking lever having means engageable with the breech ring on lowering of the breech block whereby it is rotated to retract the firing pin.

6. In a gun, a breech ring, a vertically sliding breech block in the breech ring, a firing pin in the breech block, a cocking lever pivotally mounted in the breech block above the firing pin and having means engageable with the breech ring on lowering of the breech block whereby it is rotated to retract the firing pin.

7. In a gun, a breech ring, a vertically sliding breech block in the breech ring, a firing pin in the breech block, a firing pin having a cam lug, means for cocking the firing pin, a sear slidable transversely in the breech block and arranged to be moved by the cam lug on the firing pin, a sear spring for moving the sear into the path of movement of the cam lug, a trigger car-

ried by the breech ring for retracting the sear.

8. In a gun, a breech ring, a vertically sliding breech block in the breech ring and having a recess, a firing mechanism in the block, and a trigger including a member movable into the recess when the breech block is closed and the trigger pulled to release the firing mechanism, said member movable out of the recess upon opening the block to rotate the trigger and engageable with the breech block to maintain the trigger in such rotated position. 10

9. In a breech block having a bore for a firing mechanism, a pin carried by the block and extending into the bore, a member for closing the bore, a lug on said member having a recess in its rear face engageable with the pin on turning the closing member, and a firing mechanism spring acting to normally hold the lug against the pin.

WILLIAM SUMMERBELL.
